8 Claims. (Cl. 200—48)

The present invention relates to disconnecting switches for high tension electrical power installations, particularly to air break switches of the type having a switch blade movable in an arc and rotatable about its own axis.

Air break switches of the character referred to are normally intended for outdoor installation, and in northern climates are therefore subject to icing conditions. Accordingly, it is essential that the switch be capable of freeing itself of ice and like obstructions if the switch is to be practical. One type of switch widely employed in the art affords a particularly efficient solution to the problem by imparting to the switch blade the characteristic movement of rotation within the switch contact and arcuate movement toward and away from the contact to close and open the switch. Assuming the switch to be closed, the same is opened by first imparting to the blade a predominantly rotary movement within the contact to shear any ice and free the blade end from the contact, whereafter the blade is moved arcuately out of the contact to open the switch. On closing of the switch, reverse operation occurs, i.e., the blade end is moved arcuately into the contact and then rotated into contact engagement. Because of this particular operation, the switch further affords the distinct advantage of facilitating insertion of the blade end into and removal of the blade end from the contact with reduced contact pressure thereon, and yet affords an optimum high pressure small area engagement of the blade with the contact in switch closed position. This is accomplished by flattening the blade end or forming the same of oblong or beaver tail configuration to cooperate with a generally U-shaped contact having parallel legs or leaves. The beaver tail at the blade end has a minor dimension less than the spacing between the legs of the contact and a major dimension greater than the normal spacing between the legs of the contact. The operating mechanism of the switch is so constructed and arranged that the blade end is moved into the contact at least with the beaver tail inclined to the legs of the contact to accommodate insertion of the blade end into the contact. Subsequently, the operating mechanism rotates the blade to dispose the major dimension of the beaver tail blade end transversely of the contact leaves or legs, thus to force the blade into high pressure small area engagement with the contact. On switch opening movement, the operating mechanism first rotates the blade to free the blade end from the high pressure engagement and thereafter moves the blade arcuately out of the contact.

In an early development of switches of this character, the operating means or mechanism effected the above described rotary and arcuate movements of the blade successively, but independently, so that blade rotation was effected entirely before removal of the blade end from the contact, or entirely after entry of the blade end into the contact. This switch afforded the advantages of high pressure, small area contact and ice breaking on switch opening movement, but suffered the particular disadvantage that it was not fully controlled, i.e., on closing movement of the blade, if the contact were obstructed (such as by ice in an outdoor installation), the switch blade could not be forced down through the obstruction by the operating means, but instead, the operating means could rotate the blade to complete blade movement even though the blade end were not in the contact.

2

A further development in the art, disclosed in U.S. Patents 2,231,992 and 2,527,924, afforded blade control in the region of the switch contact both in the opening and closing directions. This switch is characterized by 5 operating means for effecting simultaneous rotation and arcuate swinging of the blade, which means comprises, in terms of a conventional horizontal switch installation, a frame defining a horizontal pivot axis, a blade guide or hinge pivotally mounted on the frame, a blade carriage to which the blade is secured rotatable in the blade guide or hinge about an axis at right angles to the horizontal pivot axis, an operating crank rotatable about a vertical axis, and pivot means between the crank and blade carriage, the pivot means in the specific embodiment being disposed with its axis at 45 degrees to the horizontal and vertical, and the operating means being further characterized by intersection of the horizontal pivot axis of the blade guide or hinge, the axis of the blade, the vertical axis of rotation of the crank and the axis of the pivot 10 means in a common point. The switch as thus constructed affords particular advantages over the earlier development in the art in terms of blade control, for the operating means positively forces and drives the blade downwardly into the contact on switch closing movement, and positively removes the blade from the contact on switch opening movement. The rotary movement of the blade, while occurring simultaneously with the arcuate movement thereof, predominates in the region of the contact so that the beaver tail blade end is readily inserted 15 into and removed from the contact and is rotated an adequate extent within the contact to attain the previously described high pressure small area contact, and the desired ice breaking functions at the switch contact both upon opening and closing movements of the switch blade.

35 Other switches predicated upon the same operational characteristics have been proposed, and substantially all have proven successful in use and have been widely adopted.

40 However, two particular disadvantages have been occasioned with prior art switches; namely, (1) the tendency of the switch blade to be blown open by momentary heavy current short circuit forces, and (2) failure of the blade to close under icing conditions and/or to re-close after being blown open by short circuit forces. Both 45 of these disadvantages may in part be blamed on the flexibility of the switch blade, which in most ratings is several feet long and inherently capable of flexure or bowing.

50 The object of the present invention, generally stated, is the provision of improved switch means of the described character, and particularly improved switch means overcoming the stated disadvantages.

55 A first specific object of the invention is the provision of means preventing the switch blade from being blown out of its stationary contact and comprising a pair of latch members, one on the contact and one on the blade, which are brought into blade locking relation as the blade is rotated into high pressure engagement with the contact and which are released from one another during rotary 60 movement of the blade to release the high pressure contact engagement, whereby the latch members do not interfere with opening or closing of the blade and yet are positively engaged and are not reliant on spring catches or the like.

65 Another object of the invention is to provide means preventing the switch blade from being blown out of its contact comprising latch members as above described which prevent outward movement of the blade end, and a stop preventing excessive inward movement of the blade 70 end and serving to confine the blade end between itself and said latch means.

A second specific object of the invention is to provide

improved switch blade operating mechanism for positively driving the blade end through ice on the stationary contact despite flexure of the blade and to enhance the relationship between arcuate movement and rotation of the blade, thereby to assure proper operation of the switch under all conditions.

An additional object of the invention is to provide improved switch blade operating mechanism maintaining full control over the blade, as in prior Patents 2,231,992 and 2,527,924, yet affording even greater forces positively driving the blade arcuately into the contact and then rotating the blade through an even greater angle than heretofore.

A further object of the invention is the provision in switch means of the general character of the combination of the improved operating mechanism and said latch means, whereby attainment of the latching function is facilitated by the increased angular rotation of the blade in the contact.

Other objects and advantages of the invention will become apparent in the following detailed description.

Now, in order to acquaint those skilled in the art with the manner of making and using our improved disconnecting switch means, we shall describe, in connection with the accompanying drawings, a preferred embodiment of our switch means and the preferred manner of making and using the same.

In the drawings:

FIGURE 1 is a side elevation of a disconnecting switch embodying our invention;

FIGURE 2 is a fragmentary side elevation, on an enlarged scale, of the improved operating mechanism;

FIGURE 3 is an enlarged side elevation of the stationary contact and the end of the blade of the switch, and of the latch means of the invention;

FIGURE 4 is a cross-sectional view taken substantially on line 4—4 of FIGURE 3 showing the switch in closed position;

FIGURE 5 is a fragmentary view similar to FIGURE 4 showing the blade end during initial opening movement after about 30 degrees of blade rotation;

FIGURE 6 is a fragmentary view similar to FIGURES 4 and 5 showing the blade during opening movement after about 45 degrees of blade rotation; and

FIGURE 7 is a graph showing the relation between blade rotation and arcuate movement as imparted to the blade by the operating mechanism of the invention.

Referring now particularly to FIGURE 1 of the drawings, it will be observed that the reference character 10 designates a channel iron base that is mounted horizontally. It will be understood that the base 10 can be mounted vertically and that it can be mounted in an inverted position. For illustrative purposes, however, it is shown in a horizontal position, but it can be mounted otherwise as stated. Accordingly, the words "horizontal" and "vertical" as used in the specification and claims with respect to axes of certain elements of the switch are to be considered to express certain relative positions of the axes with respect to each other since, while the words accurately identify the axes which are illustrated in the drawing, the "vertical" and "horizontal" positions might change if the switch of this invention were mounted in other than a horizontal position.

The base 10 carries insulators 11, 12 and 13 which are of conventional construction and, as shown, may be of the pin type. The insulators 11 and 13 at the ends of the base 10 are stationary. The intermediate insulator 12 is rotatable. For this purpose a bearing 16 is mounted on the base 10 and, as will appear hereinafter, constitutes the sole bearing support for the insulator 12. Shank 17 projects below the base 10 and is arranged to receive suitable crank means for rotating the insulator 12.

The insulator 11 at the upper end carries a terminal bracket 18 that may be a bronze casting and it has a terminal pad 19 formed integrally therewith to which a

terminal connector may be secured. Mounted on the terminal bracket 18 is a generally U-shaped stationary contact assembly 21 of hard drawn copper or the like providing small area high pressure contact engaging surfaces. Reinforcing springs 22 serve to urge the arms of the contact members 21 toward each other to provide the required contact pressure.

At its upper end the insulator 13 carries a frame support 25 that may be a bronze casting and that has a terminal pad 26 for receiving a terminal connector.

The frame support 25 carries a U-shaped contact assembly 28 which is similar in construction to the contact 21 described above. The legs of the contact 28 are formed so as to provide the desired small area contact engaging surfaces which are urged toward each other by reinforcing springs. The contact member 28 is secured to the frame support 25 by bolts 30.

The U-shaped contacts 21 and 28 are interconnected in the switch closed position by a tubular switch blade 31 that may be formed of hard drawn copper. Its outer end is deformed, as shown in FIGURES 3 and 4, to define a beaver tail or oblong end portion 32 which at its sides provides small area surfaces 33 that cooperate with the corresponding contact surfaces of the legs of the contact 21.

At its other end, the switch blade 31 may be similarly deformed to provide small area contact engaging surfaces for engaging the corresponding surfaces of the contact 28.

The switch blade 31 is carried by a blade carriage 40 which may be a bronze casting suitably machined to shape. The carriage 40 is rotatably mounted in a blade hinge 44 which, as shown in FIGURES 1 and 2, is mounted by bolts 45 on the frame support 25 to rotate about a horizontal axis through the longitudinal axis of the bolts 45.

In order to rotate the blade 31 about its longitudinal axis in the blade hinge 44 and also to swing the switch blade 31 to a vertical switch open position, the blade carriage 40 is provided with an arm 46 that extends angularly downwardly and rearwardly from the longitudinal axis of the switch blade 31.

As illustrated more clearly in FIGURE 2, the arm 46 extends at an angle from the blade carriage 40 and is journaled in a bearing portion 48 of a crank pin 49 that is secured to the rotatable insulator 12 and rotates therewith when the same is turned. As will be observed from FIGURES 1 and 2, the axis of the blade, the pivot axis of the hinge 44, the axis of the arm 46 and bearing 48 and the axis of rotation of the crank 49 all intersect in a common point.

When the insulator 12 is rotated from the position shown in FIGURES 1 and 2, the switch blade 31 will be rotated about its longitudinal axis to relieve the pressure between the high pressure contact surfaces 33 and the stationary contact 21. Simultaneously, the rotation of the insulator 12 and of the crank pin 49 causes the switch blade 31 to swing about the horizontal axis through the bolts 45. Reference herein to rotation of the switch blade about its longitudinal axis to relieve pressure between it and a stationary contact is intended to cover both of the following sequences of action: (1) where the pressure is relieved and a slight separation of the contacts results from rotation of the switch blade about its longitudinal axis, even before the blade is swung arcuately out of the neighborhood of the stationary contact, and (2) where most of the pressure is relieved between the contacts but separation results only during arcuate movement of the blade out of the neighborhood of the stationary contact. It will be appreciated that our invention embraces both types of separation and either one may be had by appropriate proportioning. Correspondingly, reference herein to swinging said switch blade out of engagement with the stationary contact is intended to embrace both of the following actions (related to actions 1 and 2 set forth above): (1) where the switch blade has already separated from the stationary contact

by rotation of the switch blade about its own longitudinal axis, with the swinging movement thereafter carrying the switch blade out of the neighborhood of the stationary contact to provide a substantial air gap, and (2) where the blade has been rotated to relieve most of the pressure between it and the stationary contact but the two do not separate until the swinging movement has carried the blade out of the neighborhood of the stationary contact. When the movement of the insulator 12 has been completed the switch blade 31 is moved to the full vertical open position and it has rotated about its longitudinal axis.

The blade hinge 44 permits the switch blade 31 to rotate about its longitudinal axis and is rockably mounted on the frame support 25 about a horizontal axis through the longitudinal axis of the bolts 45 on opposite sides. Movement of the blade hinge 44 guides the switch blade 31 in its arcuate movement from the switch closed position shown in FIGURE 1 to a vertical switch open position and vice versa. Since the blade carriage 40 is fastened to the switch blade 31 and its arm 46 is rotatably mounted in the bearing portion 48 of the crank pin 49, rotation of the insulator 12 about its vertical axis causes the crank pin 49, which is secured thereto, to rotate about this vertical axis, and initially, the switch blade 31 to rotate principally about its longitudinal axis and thereafter principally about the horizontal axis through the bolts 45.

When the insulator 12 is rotated in the reverse direction, the switch blade 31 is swung to the switch closed position. At the same time the switch blade 31 is rotated about its longitudinal axis, its final rotation about this axis taking place as it approaches the horizontal position so that the final movement thereof into high pressure engagement with the contact 21 takes place while there is only a small amount of arcuate movement. This permits the necessary torque to be transmitted through the switch blade 31 for rotating it into the switch closed position with the contact surfaces under relatively high pressure.

The illustrated operating mechanism, to the extent thus far described, is very similar to the operating mechanisms of Patents 2,231,992 and 2,527,924. According to said patents, the blade operating arm 46 and the crank bearing 48 are disposed at an angle of 45 degrees to both the vertical axis of rotation of the crank and the longitudinal axis of the blade. With this arrangement, blade rotation is equal, degree for degree, with rotation of the crank 49 and arcuate swinging movement of the blade is essentially a trigonometric function of crank rotation. That is, as the crank is rotated from switch open or 90 degree position toward closed or zero position, arcuate movement of the blade is relatively rapid and predominates over blade rotation so that the blade is within about 3 degrees of its horizontal switch closed position after only 70 degrees of crank rotation, and thus 70 degrees of blade rotation. Thereafter, arcuate movement of the blade is substantially reduced and rotary movement of the blade predominates. Thus, the blade may be moved arcuately to nearly closed position with the beaver tail 32 disposed in an inclined position so that it may enter the contact with relatively slight frictional engagement with the contact leaves or legs, which pressure is continually increased as the blade moves further into the contact. Finally, after about 85 degrees of crank rotation, the blade reaches horizontal position and maintains substantially this position during further rotation of the blade into position where the beaver tail is disposed transversely between the contact legs. Since the blade has no significant arcuate movement during the last 5 degrees rotation of the crank, it follows that the blade would similarly have no significant arcuate movement during 5 degrees of over-travel of the crank, i.e., 5 degrees beyond zero position to a total travel of 95 degrees, thereby to accommodate 5 degrees additional twist of the blade. In this manner, 10 full degrees of blade rotation can be ac-

commodated without any significant arcuate movement of the blade. At the same time, full control is gained over the blade as described in the introductory portion of this specification.

5 In keeping with these operational characteristics, we have, as a prime object of our invention, provided latch means for the switch, as best shown in FIGURES 3 through 6. As shown, the latch means comprises a generally L-shaped stationary member 50 secured to the 10 terminal bracket 18 of the stationary contact 21 and extending upwardly therefrom to a position slightly below the horizontal switch closed position of the blade, to the side of the blade and immediately forwardly of the end of the blade in its closed position. At this location, the 15 latch member 50 includes an inwardly projecting horizontal leg 51 disposed transversely of the contact leaves or legs 21 and terminating a short distance inwardly of the adjacent contact leg.

The switch blade 31 at its outer end is provided with 20 a conventional arcing horn 52 suitably in the form of a looped wire rod, the inner ends of which are anchored in the beaver tail end portion 32 whereby the horn is mounted for conjoint rotary and arcuate movement with the blade. The wire rod at the side of the horn adjacent the member 50 is so formed as to define a downwardly 25 extending loop or hook 53 which in the closed position of the switch blade engages beneath the latch portion 51 of the member 50. In this position, as shown in FIGURES 3 and 4, the latch members 51 and 53 positively prevent upward movement of the blade and thus positively prevent the blade from being blown upwardly out of its contact by momentary heavy current short circuit forces.

When it is desired to open the switch, initial rotation 35 of the crank 49 will initially impart predominantly rotary movement to the blade 31 and the arcing horn 52. As shown in FIGURES 4 to 6, the latch member 53 defined by the arcing horn is displaced a significant distance from the axis of rotation of the blade and is also displaced from 40 the contact engaging surfaces 33 in a direction transverse to the beaver tail or oblong end portion 32. Consequently, as the blade is rotated about its axis, substantial arcuate movement is imparted to the latch 53 whereby the same is rotated, as shown in FIGURE 5, to a position wherein it clears the latch 51 before there is any significant arcuate movement of the blade 31. Thereafter, the 45 latch members 51 and 53 pose no obstacle to arcuate movement of the blade 31, so that the blade may be swung arcuately out of the contact in the same manner as always.

50 As assistive means for the latching operation, we prefer to provide a transverse stop member 54 in the contact structure between the leaves or legs thereof so as positively to define the horizontal closed position of the switch blade. With the stop 54 in proper position, the 55 blade, upon closing movement, will enter the contact at an inclination, somewhat as shown in FIGURE 6, and be moved downwardly into the contact until the edge of the oblong end portion 32 adjacent the latch 51 engages the stop 54. During this movement, the latch 53 is of course disposed to one side of the latch 51 so that no obstacle is presented to full entry of the blade end into the contact. Then, the blade will be rotated about its 60 axis to cause the latch 53 to be swung in under the latch 51 (said latch being disposed substantially immediately above only the terminal portion of the arc of movement of the latch 53). Further rotary movement of the crank 49 will then cause the blade to rotate fully into the position where the oblong end portion 32 is disposed perpendicular to the legs of the contact leaves 21 and will simultaneously 65 impart a slight upward movement to the blade until the latch 53 is brought into positive engagement with the latch 51, whereupon the two latch members positively prevent any further movement of the blade and its operating mechanism. In this position, the blade end 70 is positively locked against any significant degree of in-

advertent movement relative to the contact structure since the latches 51 and 53 prevent the same from being blown upwardly out of the contact and the stop 54 prevents the blade end from being moved downwardly an excessive degree into the contact. Thus, the blade effectively becomes locked between the stop 54 and the latch means 51-53.

This positively locked blade feature will allow the momentary current rating of a particular blade and contact combination to be increased and, consequently, will permit a reduction in the number of contacts required in a multiple unit contact assembly for a given momentary current rating. It therefore represents a substantial saving for the switch manufacturer, as well as positive assurance for the user that the switch blade cannot be blown open by mechanical forces caused by heavy current.

In addition the latch members 51 and 53 constitute a positive limit stop for the closing operation of the blade, so that closed position stops previously provided in switches of the general character may now be eliminated. Specifically, the closed position stops 55 and 51 shown in FIGURE 10 of Patent 2,231,992 are no longer necessary, since the latch members of the present invention perform this function as one of their attributes.

Further to enhance the operational characteristics of switches of the general character, we provide as a second object of our invention improved operating mechanism for such switches. The present invention particularly utilizes the concept and attains all of the advantages of the operating mechanisms shown and described in Patents 2,231,992 and 2,527,924, and provides very substantial improvements therein, especially compensation for blade flexure, assurance of closing under all conditions and improved opening and closing performance, all by the apparently simple procedure of changing the relative angle of the arm 46 and bearing 48. Specifically, by increasing the angular relationship over the 45 degree angle previously dictated, the present invention provides for arcuate travel of the blade through a greater arc of movement thereby compensating for blade flexure and assuring closing under all conditions, and simultaneously provides a substantially greater period of arcuate quiescence of the blade and a correspondingly greater twisting of the blade within the contact thereby to enhance opening and closing operations under all conditions. The variants of the angular relationship from the prior art need only be a degree or two to achieve our new results.

Referring to FIGURES 2 and 7, we have illustrated herein a preferred embodiment of the improved operating mechanism of our invention. As shown, the mechanism is the same as that of the above discussed prior art with the exception that the angles between the axis of the arm 46 and bearing 48 and the axes of the blade 31 and the crank 49 have been increased to 46 degrees. By maintaining these two angles equal, the blade will have a vertical open position and blade rotation will be maintained at a linear 1 to 1 ratio to crank rotation, as depicted by the straight inclined line in FIGURE 7. However, by virtue of this change the operating mechanism will now impart 92 degrees of arcuate swing to the blade (blade swing being equal to the sum of two changed angles) and the flattened end of the blade, following the curve depicted in FIGURE 7, will become disposed in blade closed or zero arcuate position after only about 75 degrees of movement in the closing direction. Throughout the last 15 degrees of crank rotation before reaching absolute zero, the blade could dip 2 degrees below zero position as indicated by the dotted line in FIGURE 7. However, by virtue of the stop 54 provided in the stationary contact assembly, the blade is caused to stop at zero horizontal position and to be maintained in said position during the continued rotation of the crank 49 and thus of the blade 31. Since there is substantially no lost motion in the operating mechanism, the structural

assembly results in considerable force being applied to the blade such as actually to flex the blade as a normal part of its closing operation whereby extremely high pressure is applied to the end of the blade positively to drive the blade fully down into the contact and to break up any ice that may tend to bridge between the contact leaves or legs and/or accumulate on the position stop 54. In this manner, blade closing force is greatly amplified over that heretofore available and compensates effectively for the flexibility of the blade, thereby positively to insure complete, accurate closing of the blade upon each operation.

As above stated, and as revealed by the graph of FIGURE 7, the flattened or oblong end portion 32 of the switch blade completes its arcuate swing after only about 75 degrees of movement in the closing direction, and is then retained in zero arcuate position throughout the last 15 degrees of crank rotation. Now, by providing 15 degrees of over-travel (as contrasted to the prior art 5 degree of over-travel) to permit the blade to return to a relaxed condition in zero arcuate position, 30 degrees of crank rotation and thus 30 degrees of blade rotation is accommodated without any, or certainly no more than minimal, arcuate movement of the blade.

Referring to FIGURES 4 to 6, the blade is illustrated in fully closed position in FIGURE 4. Upon blade opening rotation of the crank 49, the blade will initially and simultaneously start to rotate and to dip slightly thereby to open a slight gap between the latch members 51 and 53 to facilitate disengagement of the same. The blade end 32 at the edge thereof adjacent the latches will then engage the stop 54, whereafter only rotary movement is imparted to the blade throughout an arc of 30 degrees. At this point, as shown in FIGURE 5, the beaver tail or oblong end portion 32 of the blade is not only relieved of high pressure engagement with the contact leaves or legs 21 but is actually completely free of said leaves. The blade will then simultaneously rotate and commence its arcuate rise, until at 45 degrees crank rotation it will have cleared the contact structure substantially entirely, as revealed in FIGURE 6.

The greatly increased rotation of the blade end afforded according to this invention results in four significant improvements in operating performance: (1) Since the blade is rotated through such a large angle, ice breaking on switch opening and on switch closing is greatly enhanced. (2) Since the blade is freed entirely from the contact structure, there is no contact resistance to removal or insertion of the blade whereby energy is conserved and/or is rendered available for ice breaking functions, and the blade and contact are subject to substantially less wear than heretofore. (3) Due to the increased rotation, the flattened blade end or beaver tail may be made broader than heretofore without disadvantageous results, thereby to facilitate increased contact pressures in the fully closed position of the switch. (4) The increased rotation enhances the operability and functioning of the latch means of this invention.

The above stated specific operational characteristics and advantages are, as stated, attained by increasing the angles between the arm 46 and the axis of the blade and between the arm 46 and the axis of the crank 49 to 46 degrees. Further increase, and/or variable increase of these angles will result in slightly varied operational characteristics which may be utilized for a variety of purposes. For the specific objectives of the present invention, we prefer that the described angles be maintained within the range of from about 46 degrees to about 48 degrees.

In view of the foregoing, it will be appreciated that the present invention provides substantial advantages in switches of the general character. Specifically, the latch means obviates the problem of inadvertent switch opening under overload, permits use of simplified and more economical contact structures and substitutes for position

stops heretofore required; the improved operating mechanism enhances switch operation and renders the same positive and fully reliable by compensating for blade flexure, increasing the closing forces and accommodating greater blade twist in the critical range of switch operation; and the combination of these features provides a cooperative, complementary relationship resulting in a substantially improved switch structure. Thus, the objects and advantages of the invention have been shown herein to be attained in a convenient, economical and practical manner.

While we have shown and described what we regard to be the preferred embodiment of our invention, it will be appreciated that various changes, rearrangements and modifications may be made therein without departing from the scope of the invention, as defined by the appended claims.

We claim:

1. In a switch having a generally U-shaped stationary contact and a switch blade arcuately swingable into and out of the contact to close and open the switch, said blade having an oblong end portion enterable into the contact and being rotatable in one direction upon closing of the switch to dispose said end portion transversely of the contact and effect high pressure engagement of said end portion with the legs of the contact and being rotatable in the opposite direction upon opening of the switch to dispose said end portion in a relatively inclined position and relieve said high pressure engagement prior to significant arcuate movement of the blade; the improvement comprising a first latch member on the blade, said first latch member being displaced from the axis of rotation of the blade and being displaced transversely downward from the oblong blade end portion adjacent the edge thereof first entering the contact upon closing movement of the blade, and a second latch member on said contact below the closed position of the blade and extending transversely of the legs of the contact in the direction opposed to the direction of rotation of said first latch member upon closing movement of the blade, said second latch member including a downwardly facing latch surface disposed substantially immediately above the terminal portion only of the arc of rotation of the first latch member upon rotation of the blade in its closing movement, said first latch member engaging the latch surface of said second latch member in its closed position and terminating closing movement of the blade, said first latch member upon opening movement of the blade rotating clear of said second latch member prior to significant arcuate movement of the blade.

2. In a switch having a generally U-shaped stationary contact and a switch blade arcuately swingable into and out of the contact to close and open the switch, said blade having an oblong end portion enterable into the contact and being rotatable in one direction upon closing of the switch to dispose said end portion transversely of the contact and effect high pressure engagement of said end portion with the legs of the contact and being rotatable in the opposite direction upon opening of the switch to dispose said end portion in a relatively inclined position and relieve said high pressure engagement prior to significant arcuate movement of the blade; the improvement comprising a first latch member on the blade, said first latch member being displaced from the axis of rotation of the blade and being displaced transversely downward from the oblong blade end portion adjacent the edge thereof first entering the contact upon closing movement of the blade, a second latch member on said contact below the closed position of the blade and extending transversely of the legs of the contact in the direction opposed to the direction of rotation of said first latch member upon closing movement of the blade, and a stop in the contact preventing movement of the oblong end portion of the blade beyond switch closing position and retaining said end portion in such position whereby said blade is

rotated through a substantial angle while the blade end portion is retained against arcuate movement, said second latch member including a downwardly facing latch surface disposed substantially immediately above the terminal portion only of the arc of rotation of the first latch member upon rotation of the blade in its closing movement, said first latch member engaging the latch surface of said second latch member in its closed position and terminating closing movement of the blade, the blade in its closed position being effectively locked in such position by said stop and said latch members, said first latch member upon opening movement of the blade rotating clear of said second latch member prior to significant arcuate movement of the blade.

3. In a disconnecting switch having a stationary generally U-shaped contact and a switch blade with an end providing small area contact engaging surfaces, the blade being arcuately swingable from a vertical switch open position to a horizontal switch closing position with said end in the contact, the blade being rotatable about its axis in one direction upon switch closing movement to dispose said end transversely of the contact to move said surfaces into high pressure engagement with the contact and being rotatable in the opposite direction upon switch opening movement to dispose said end in a relatively inclined position to free it from the contact; operating mechanism for said plate comprising a stationary frame spaced horizontally from said contact, a blade hinge pivotally mounted on said frame on a horizontal axis transverse to the blade, a blade carriage fixed to said blade and rotatably mounted on said hinge coaxially of the blade, an arm extending angularly from said carriage, and a crank rotatably connected with said arm and mounted for rotation about a vertical axis, the axes of the blade, the hinge, the arm and the crank intersecting substantially in a common point and said arm extending at an angle of more than 45 degrees to both said vertical axis and the axis of the blade; said crank upon rotation through an angle in excess of 100 degrees rotating said blade through a substantially equal angle and imparting arcuate swinging movement to said blade through an arc in excess of 90 degrees wherein the arcuate swing imparted to the blade end adjacent horizontal switch closing position is relatively insignificant during rotary movement of the blade through an angle in excess of 20 degrees; a first latch member on the blade, said first latch member being displaced from the axis of rotation of the blade and from the contact engaging surfaces thereof in the direction generally of the plane of arcuate blade movement, and a second latch member on said contact extending transversely thereof in the direction opposed to the direction of rotation of said first latch member upon closing movement of the blade, said second latch member being disposed substantially immediately above the terminal portion only of the arc of rotation of the first latch member upon rotation of the blade in its closing movement to cause said first latch member to engage beneath said second latch member on closing of the blade and to cause said first latch member to rotate clear of said second latch member prior to significant arcuate movement of the blade.

4. In a disconnecting switch having a stationary generally U-shaped contact and a switch blade with an oblong end portion providing small area contact engaging surfaces, the blade being arcuately swingable from a vertical switch open position to a horizontal switch closing position with said end in the contact, the blade being rotatable about its axis in one direction upon switch closing movement to dispose said oblong end portion transversely of the contact to move said surfaces into high pressure engagement with the contact and being rotatable in the opposite direction upon switch opening movement to dispose said oblong end portion in a relatively inclined position to free it from the contact; operating mechanism for said blade comprising a stationary frame spaced hori-

zontally from said contact, a blade hinge pivotally mounted on said frame on a horizontal axis transverse to the blade, a blade carriage fixed to said blade and rotatably mounted on said hinge coaxially of the blade, an arm extending angularly from said carriage, and a crank rotatably connected with said arm and mounted for rotation about a vertical axis, the axes of the blade, the hinge, the arm and the crank intersecting substantially in a common point and said arm extending at an angle in the order of about 46 to 48 degrees to both said vertical axis and the axis of the blade, the hinge, the arm and the crank intersecting substantially in a common point and said arm extending at an angle in the order of about 46 to 48 degrees to both said vertical axis and the axis of the blade, said crank upon rotation through an angle in the order of about 105 degrees rotating said blade through a substantially equal angle and imparting arcuate swinging movement to said blade through an arc in excess of 90 degrees wherein the arcuate swing imparted to the blade adjacent horizontal switch closing position is relatively inconsequential during rotary movement of the blade through an angle of at least about 30 degrees; a first latch member on the blade, said first latch member being displaced from the axis of rotation of the blade and being displaced transversely from the oblong end portion of the blade adjacent the contact engaging surface thereof first entering the contact upon closing movement of the blade, and a second latch member on said contact extending transversely thereof in the direction opposed to the direction of rotation of said first latch member upon closing movement of the blade, said second latch member being disposed substantially immediately above the terminal portion only of the arc of rotation of the first latch member upon rotation of the blade in its closing movement to cause said first latch member to engage beneath said second latch member and terminate closing movement of the blade and to cause said first latch member to rotate clear of said second latch member prior to significant arcuate movement of the blade on opening of the blade.

5. In a disconnecting switch as set forth in claim 4, a stop in said contact preventing movement of said blade end beyond a substantially horizontal position wherein said first latch member is maintained adjacent said second latch member, said stop preventing arcuate movement of said oblong end portion of said blade beyond switch closing position, whereby said blade is rotated through a substantial angle while the blade end is retained against arcuate movement.

6. In a disconnecting switch having a stationary generally U-shaped contact and a switch blade with an end providing small area contact engaging surfaces, the blade being arcuately swingable from a vertical switch open position to a horizontal switch closing position with said end in the contact, the blade being rotatable about its axis to move said surfaces into and out of high pressure engagement with the contact; operating mechanism for said blade comprising a stationary frame spaced horizontally from said contact, a blade hinge pivotally mounted on said frame on a horizontal axis transverse

to the blade, a blade carriage fixed to said blade and rotatably mounted on said hinge coaxially of the blade, an arm extending angularly from said carriage, and a crank rotatably connected with said arm and mounted for rotation about a vertical axis, the axes of the blade, the hinge, the arm and the crank intersecting substantially in a common point and said arm extending at an angle of more than 45 degrees to both said vertical axis and the axis of the blade; said crank upon rotation through an angle in excess of 100 degrees rotating said blade through a substantially equal angle and imparting arcuate swinging movement to said blade through an arc in excess of 90 degrees wherein the arcuate swing imparted to the blade adjacent horizontal switch closing position is relatively inconsequential during rotary movement of the blade through an angle in excess of 20 degrees.

7. In a disconnecting switch having a stationary generally U-shaped contact and a switch blade with an end providing small area contact engaging surfaces, the blade being arcuately swingable from a switch open position to a horizontal switch closing position with said end in the contact, the blade being rotatable about its axis to move said surfaces into and out of high pressure engagement with the contact; operating mechanism for said blade comprising a stationary frame spaced horizontally from said contact, a blade hinge pivotally mounted on said frame on a horizontal axis transverse to the blade, a blade carriage fixed to said blade and rotatably mounted on said hinge coaxially of the blade, an arm extending angularly from said carriage, and a crank rotatably connected with said arm and mounted for rotation about a vertical axis, the axes of the blade, the hinge, the arm and the crank intersecting substantially in a common point and said arm extending at an angle in the order of about 46 to 48 degrees to both said vertical axis and the axis of the blade; said crank upon rotation through an angle in the order of about 105 degrees rotating said blade through a substantially equal angle and imparting arcuate swinging movement to said blade through an arc of at least about 92 degrees wherein the arcuate swing imparted to the blade adjacent horizontal switch closing position is relatively inconsequential during rotary movement of the blade through an angle of at least about 30 degrees.

8. In a disconnecting switch as set forth in claim 7, a stop in said contact preventing movement of the oblong end portion of said blade beyond horizontal position, said stop retaining said end portion of said blade in switch closing position whereby said blade is rotated through a substantial angle while the blade end is retained against arcuate movement.
